UNITED STATES PATENT OFFICE.

MARCUS D. BOUGHTON, OF JEFFERSON, NEW YORK.

DELIVERY MECHANISM.

1,374,981.

Specification of Letters Patent.

Patented Apr. 19, 1921.

Application filed December 4, 1920. Serial No. 428,310.

To all whom it may concern:

Be it known that I, MARCUS D. BOUGHTON, a citizen of the United States, and a resident of Jefferson, in the county of Schoharie and State of New York, have invented certain new and useful Improvements in Delivery Mechanisms, of which the following is a specification.

This invention relates to sheet delivery mechanisms, and particularly to that class thereof adapted for delivering plates or sheets from some source of supply into a stack for removal. The object of my improvements is to provide a device of the class specified, simple in construction and which will operate automatically and deliver the sheets with accuracy and speed.

With these ends in view and others which will appear hereinafter, my improvements comprise features which are illustrated in their preferred embodiment in the drawings accompanying this specification wherein:

Figure 1 is a side elevation of the delivery end of a drying oven, including a sectional view on line 1-1 of Fig. 2 of a portion of my improvements. Fig. 2 is a front end elevation, partly in section on line 2-2 of Fig. 1, of what is shown in said Fig. 1 and showing further details of the device. Fig. 3 is a side elevation, looking in the direction of arrow 3 of Fig. 2. All the figures of the drawings are to one scale.

My improvements are illustrated as applied to the delivery of plates such as of tin from a drying oven 4, through which said plates are passed by means of endless chain 5 carrying skeleton wings 6. The plates are deposited between said wings 6 respectively, as at 7, by means not shown, from some source of supply, such as a coating machine not shown. The plates lie against said wings 6 with their coated faces uppermost, as at 8, as they are carried through the oven by said chain. As the plates are advanced by the lower run of the chain toward their place of delivery, their lower edges respectively drag along on guideway table 9 on the oven bottom 4^a and, as they reach a point just below the axis of sprocket 10, each plate encounters one or more toothed wheels as 11 rotating at a surface speed in excess of that of chain 5. Plate 7^a has just encountered said wheel and plate 7^b has just passed out of engagement therewith. At the same time wing 6^a has passed upwardly in its curved path around sprocket 10 there-

by moving out of the path of plate 7^b driven forwardly by wheel 11. The function of said toothed wheels 11 is to lift and advance the plate, thereby freeing it from any adhesion to the wing which has impelled it through the drying oven.

Moving forwardly, as indicated by its arrow, over guideway table 9 are feed chains 12, 12 traveling at about the speed of the outer ends of wings 6 as they pass about sprocket 10. These chains are supported on sprockets as 13, 14 and may be driven from shaft 15 of sprocket 14, by means not shown. Guideway table 9 is inclined upwardly at 9^a to conform to the path of travel of the ends of wings 6 as they pass about sprocket 10 and farther on, at 9^b, said table is inclined downwardly to permit the plates to slide off from chains 12, 12 onto a series of horizontal rolls 16, 17, 18, 19, preferably having their axes at right angles to the axes of sprockets 10, 13 and 14. Said rolls form a roller table for the reception and advancement of the plates.

Rolls 17, 18 are rotated by belt 20, from means not shown, in clockwise direction, Fig. 2, and rolls 16, 19 may be similarly driven if desired. Said rolls are driven at sufficient speed to advance a plate delivered thereon by chains 12, away from receiving position 7^a on rolls 16, 17, before the next succeeding plate 7^b is delivered onto said rolls.

Pivoted to base 21, which supports rolls 16, 17, 18, is lift-frame 22. Said frame, preferably pivoted coaxially with roll 18, comprises two side members 23, 24 having downwardly reaching side wings as 24^a which act as side guides to the plates deposited therebetween. Said side members, which terminate in handles as 24^b, are tied together near their outer ends by front wall 25 which acts as a stop and gage plate 100 against which the plates are delivered. Rear wall 26 is pivoted at its upper end to side members 23, 24 of lift-frame 22.

Said front wall 25 and rear wall 26 rest upon table 27 having legs 28, 28, so that a truck may be run under said table for removing it when filled with plates. Lift-frame 22 may be provided with counterbalance 29 extending rearwardly from its pivot. Reaching forwardly from back plate 110 26 and pivoted to opposite vertical edges thereof are arms as 31 having hooks 33 for

engagement with pins as 34 on the vertical edges of front wall 25 for holding said back plate in place. Said arms as 31 may be connected by front bar 32 if desired. For free-
5 ging said hooks from their pins respectively when it is desired to raise the lift-frame, links 35, 36 connecting said arms with levers 37, 38 pivoted to the respective side mem-
10 bers 23, 24, are provided. Said levers 37, 38 terminate outwardly in handles just under the handles respectively of side members
15 23, 24.

Extending between side members 23, 24, between rolls 18, 19 is stop wall 40, efficient 15 when lift-frame 22 is raised, for preventing any plate from being delivered therebeyond.

The operation of my improved delivery mechanism will be readily understood from the foregoing description and may be briefly 20 set forth as follows: As the plates 7 are advanced by wings 6 of the drier chain plate, 7^a encounters toothed wheels 11 by which it is raised and advanced ahead of its impelling wing to position 7^b, where the lower 25 edge thereof rests on chains 12 by which it is advanced forwardly and upwardly until it passes over the high portion of the chains as they pass over sprockets 13. The plate then slides through position 7^a onto rolls 30 16, 17, position 7^b, where its further movement in that direction is prevented by wall 39 of base 21. From there said rolls advance the plate at right angles to its previous direction of travel onto rolls 18, 19 35 and thence between lift-frame members 23, 24 and between end walls 25, 26 which with the depending sides as 24^a of frame mem-
bers 23, 24, form a receiving box for the plates. When this box is sufficiently filled
40 the handles of levers 37, 38 are lifted into contact with the handles of side members 23, 24, thereby unlatching the hooks, as 33, from their respective pins whereby back wall 26 is free. Then both sets of handles
45 are lifted together to the dotted position of Fig. 2 whereby the pile of plates is free for removal with table 27. While said frame is in lifted position any plate advanced by rolls 16, 17, 18 will be prevented
50 from being delivered by stop wall 40.

I claim:

1. In sheet delivery mechanism the combination of a traveling conveyer adapted for advancing sheets on edge, and a toothed 55 wheel rotated at a peripheral speed in ex-
cess of that of the traveling conveyer and adapted to engage the lower edges of successive sheets advanced by said conveyer and lift and advance said sheets away from the 60 engaging portions of said conveyer respec-
tively.

2. In sheet delivery mechanism the combination of a traveling conveyer adapted for advancing sheets on edge, a toothed 65 wheel rotated at a peripheral speed in ex-

cess of that of the traveling conveyer and adapted to engage the lower edges of successive sheets advanced by said conveyer and lift and advance said sheets away from the 70 engaging portions of said conveyer respec-
tively, and an endless chain driven at a speed in excess of that of the traveling conveyer and adapted to engage and advance the lower edges of successive sheets after they are advanced by said wheel. 75

3. In sheet delivery mechanism the combination of a traveling conveyer adapted for advancing sheets on edge, a toothed wheel rotated at a peripheral speed in excess of that of the traveling conveyer and adapted 80 to engage the lower edges of successive sheets advanced by said conveyer and lift and advance said sheets away from the engaging portions of said conveyer respec-
tively, and a plurality of rotating rolls 85 forming a roller table adapted for receiving the sheets from the previous advancing means and further advancing said sheets.

4. In sheet delivery mechanism the combination of a traveling conveyer adapted for 90 advancing sheets on edge, a toothed wheel rotated at a peripheral speed in excess of that of the traveling conveyer and adapted to engage the lower edges of successive sheets advanced by said conveyer and lift 95 and advance said sheets away from the engaging portions of said conveyer respec-
tively, an endless chain driven at a speed in excess of that of the traveling conveyer and adapted to engage and advance the 100 lower edges of successive sheets after they are advanced by said wheel, and a plurality of rotating rolls forming a roller table adapted for receiving the sheets from the previous advancing means and further ad- 105 vancing said sheets.

5. In sheet delivery mechanism the combination of a traveling conveyer adapted for advancing sheets on edge, a plurality of rotating rolls forming a roller table adapted 110 for receiving the sheets from the previous advancing means and further advancing said sheets, a lift-frame pivotally attached to said roller table, adapted for receiving the sheets from said table, and including 115 rigid side wings, a rigid front wall and a movable rear wall, means for locking said rear wall in position, and means for releasing said locking means before raising said lift-frame to free the accumulated sheets. 120

6. In sheet delivery mechanism the combination of a traveling conveyer adapted for advancing sheets on edge, a plurality of rotating rolls forming a roller table adapted 125 for receiving the sheets from the previous advancing means and further advancing said sheets, a lift-frame pivotally attached to said roller table, adapted for receiving the sheets from said table, and including rigid side wings, a rigid front wall and a 130

movable rear wall, said movable rear wall being pivotally attached to said lift-frame, a hook arm connecting said rear wall with a fixed portion of said lift-frame, and hand operated means for releasing said hook arm from its connection.

7. In sheet delivery mechanism the combination of a traveling conveyer adapted for advancing sheets on edge, a plurality of rotating rolls forming a roller table adapted for receiving the sheets from the previous advancing means and further advancing said sheets, a lift-frame pivotally attached to said roller table, adapted for receiving the sheets from said table, and including rigid side wings, a rigid front wall and a movable rear wall, and a stop wall on said lift-frame adapted to be interposed into the path of said sheets when the lift-frame is raised.

8. In sheet delivery mechanism the combination of a traveling conveyer adapted for advancing sheets on edge, a plurality of rotating rolls forming a roller table adapted for receiving the sheets from the previous advancing means and further advancing said sheets, a lift-frame pivotally attached to said roller table, adapted for receiving the sheets from said table, and including rigid side wings, a rigid front wall and a movable rear wall, said movable rear wall being pivotally attached to said lift-frame, means for

locking said rear wall in position, means for releasing said locking means before raising said lift-frame to free the accumulated sheets, and a stop wall on said lift-frame adapted to be interposed into the path of said sheets when the lift-frame is raised.

9. In sheet delivery mechanism the combination of a traveling conveyer adapted for advancing sheets on edge, a pivotally mounted lift-frame, adapted for receiving the sheets from said conveyer and including rigid side wings, a rigid front wall and a movable rear wall, means for locking said rear wall in position, and means for releasing said locking means before raising said lift-frame to free the accumulated sheets.

10. In sheet delivery mechanism the combination of a traveling conveyer adapted for advancing sheets on edge, a pivotally mounted lift-frame, adapted for receiving the sheets from said conveyer and including rigid side wings, a rigid front wall and a movable rear wall, said movable rear wall being pivotally attached to said lift-frame, a hook arm connecting said rear wall with a fixed portion of said lift-frame, and hand operated means for releasing said hook arm from its connection.

In witness whereof, I hereby affix my signature this 2d day of December, 1920.

MARCUS D. BOUGHTON.
